UNITED STATES PATENT OFFICE.

WILLIAM DEMUTH, OF NEW YORK, N. Y.

DESIGN FOR A PIPE.

SPECIFICATION forming part of Design No. 25,564, dated June 2, 1896.

Application filed April 15, 1896. Serial No. 587,736. Term of patent 7 years.

To all whom it may concern:

Be it known that I, WILLIAM DEMUTH, a citizen of the United States, residing at New York, in the county and State of New York, 5 have invented and produced a new and original Design in Pipe-Stems, of which the following is a specification.

In this specification reference is had to the accompanying drawing, which shows a perspective view of a tobacco-pipe stem formed according to my new design.

The leading feature of my design consists in a pipe-stem having a twist between the mouthpiece and the bowl.

15 A is the bowl of a tobacco-pipe. B is the mouthpiece, and C is the stem. This stem is

formed with a twist *a*, which imparts to the same a novel and distinguished appearance. Between the twist *a* and the tip of the mouthpiece the stem *C* has an opening *b*, and on the opposite side of said twist is an opening *c*.

What I claim as new, and desire to secure by Letters Patent, is—

The design for a tobacco-pipe stem, substantially as shown and described. 25

In testimony whereof I have hereunto set my hand in the presence of two subscribing witnesses.

WILLIAM DEMUTH.
